UNITED STATES PATENT OFFICE.

JUAN H. REECE, OF JOLIET, ILLINOIS, ASSIGNOR TO HUMPHREY & SONS, OF JOLIET, ILLINOIS,
A COPARTNERSHIP.

GRIPPER FOR WIRE.

No. 922,814.

Specification of Letters Patent.

Patented May 25, 1909.

Application filed July 2, 1907. Serial No. 381,905.

To all whom it may concern:

Be it known that I, JUAN H. REECE, a citizen of the United States, residing at Joliet, in the county of Will and State of Illinois, have invented certain new and useful Improvements in Grippers for Wire, of which the following is a specification.

The gripper of the present invention is specially adapted and intended for use in placing the wire into position for winding on the drawing block, for which purpose the gripper should be of a construction to firmly grip the wire and be capable of a free connection with the drawing block, so as to be drawn toward and onto the block as the block revolves, carrying with it the caught wire.

The objects of the present invention are to construct a gripper adapted for direct connection with the drawing block, and so formed as to grip the end of the wire and carry the gripper with the wire directly onto the revolving block; to construct a gripper having a frame or head carrying a pair of gripping jaws arranged at an inclination to each other, each jaw having a gripping face to bite or grip the wire; to furnish means for holding the gripper jaws in their advanced position under a yieldable pressure which will allow of the insertion of the wire; and to improve generally the construction, arrangement and operation of the gripper as a whole.

The invention consists in the features of construction and combination of parts hereinafter described and claimed.

In the drawings Figure 1 is a longitudinal sectional plan view of the gripper; Fig. 2 a longitudinal sectional elevation of the gripper; Fig. 3 an end elevation of the gripper; Fig. 4 a perspective view of the gripper jaw; and Fig. 5 a front elevation of a wire drawing block, showing the gripper of the invention connected therewith.

The gripper of the present invention has a plate or body 1, with an eye or loop 2 at its rear end, for the attachment of the gripper, as a whole, to a chain or other connection, by which the gripper can be applied to a wire drawing block. The gripper has, on each side of the body or plate 1, inclined sockets 3, each socket having a passage 4, and the two sockets coming together at the front end, and forming an apex or nose 5, with a flat face, in the construction shown. Each passage or

hole 4 has entered thereinto a gripper jaw 6, each gripper jaw having an acting face 7 at the front end; and each acting face, as shown, is provided with serrations or teeth 8 to effect a firm bite on the wire, but the serrations or teeth could be omitted if so desired. Each gripper jaw, at its front end, has a semi-countersink 9, to facilitate the entering of the end of the wire between the acting faces of the jaws, and, as shown, the body or plate of the gripper has a longitudinal hole 10 in line with the teeth or serrations, for the passage of the end of the wire a sufficient distance within the gripping faces of the jaws, to insure a firm bite or grip on the wire, by which the wire will be held firmly between the gripper jaws. The body or plate 1, in the construction shown, has openings or holes 11, and, as shown, the passage 10 opens into the front hole 11, and the wire 12, after passing between the acting faces of the gripper jaws, can enter the passage 10 and into the front opening 11, as shown in Fig. 1.

A coiled spring 13 is located in each passage or hole 4, and one end of the coiled spring abuts against the rear end of each gripper jaw, and the other end of each coiled spring abuts against a block 14 secured in the hole 4 of the socket or tube 3 at its rear end by a cross pin 15 or otherwise, and one of the heads or blocks 14 has formed thereon, or secured thereto, an eye 16, for the attachment of a chain or other flexible connection when the gripper is used with a wire drawing block.

In use, whether with a drawing block, or otherwise, the end of the wire is entered between the gripping faces of the gripper jaws, such entrance of the wire being permitted by the retraction of the jaws through the yield of the coiled springs 13 in entering the wire, and after the end of the wire is entered between the acting faces of the gripper jaws a backward draw or pull on the gripper, from the eye or loop 2 and the chain or other connection secured to the eye or loop, will cause the body or plate to recede, and such recession of the body or plate will, through the inclination of the passages or holes 4, serve to project the gripper jaws, and force such jaws forward and inward so as to firmly bite or grip the wire, and such bite or grip on the wire will continue so long as a rearward draw is applied to the gripper body or plate.

The gripper of the present invention is of simple construction, and enables the end of the wire to be readily entered between the gripping faces of the jaws, and a rearward or 5 receded movement of the gripper body or plate will at once act and force the acting faces of the gripper jaws toward each other, so as to firmly bite or grip the end of the wire, and such bite or grip will continue as 10 long as a force is exerted to draw rearward on the gripper body or plate, thus enabling a single grip or bite to be continued without releasing the wire until the drawing operation of the wire to the amount required is 15 finished.

The gripper of the present invention is shown, in Fig. 5, as connected with a wire drawing block by a chain 17 attached to the eye or loop 2 and to the block, and a chain 20 18 attached to the eye or loop 16 and to the block, so as to furnish a flexible connection between the gripper and the wire drawing block by which the gripper can be drawn down to position to bite or grip the 25 end of the wire after passing the drawing die. The wire drawing block 19 can be of any usual and well known construction, and is raised to stop the revolution thereof by lift or push arms 20 located on opposite 30 sides of the block, and engaging with the under face of the block as usual. Each push or lift arm 20 is connected by a pin or pivot 21 with a cradle 22 mounted on a pivot 23 in a bracket arm 24, so that the cradle 35 can swing on the pivot to raise and lower the lifting or push rods or bars. The free end of the cradle has an eye to which is connected one end of a rod 25, the other end of which is connected with a kick-off lever 26 40 operating in connection with stops 27 and 28 as usual. The wire drawing block, when lowered, is driven by a shaft 29 through intermeshing gears 30 and 31, the latter of which is driven by a shaft 32 as usual. A 45 frame formed of a lower longitudinal beam 33, vertical posts 34, and an upper longitudinal beam 35 supports the block and operating bars as usual, and a draw die 36, of the usual construction, is located adjacent to 50 the block.

The gripper of the present invention is well adapted for use with a wire drawing block, as it can be connected directly with the block and be drawn down to enter the 55 end of the wire between the acting faces of

the gripper jaws so that, as the block is revolved, a rear draw will be furnished for the gripper body or plate by which the gripper jaws will be made to firmly grip or bite the end of the wire, and inasmuch as the wire 60 must be drawn forward with the gripper, it follows that a single grip is all that is necessary to bring the wire into position to wind onto the wire drawing block, thus dispensing with the necessity of making several grips or 65 bites on the end of the wire before the wire is drawn into position to be caught by the block and wound thereon, which makes a considerable saving, as, instead of several 70 grips or bites, which destroy the wire, only one grip or bite is necessary with the gripper of the present invention connected directly with the drawing block.

The gripper of the present invention, while specially applicable for use with a drawing 75 block, can be used with other appliances, and for other purposes than drawing wire, where a gripper is wanted which will firmly grip or bite the wire by and through a rearward draw on the body or plate of the gripper, for the 80 draw on the body or plate of the gripper to act and force inward the acting faces of the gripper jaws.

What I claim as new and desire to secure by Letters Patent is:

In a gripper for wire, the combination of a plate, forwardly converging longitudinal socket members, one on each side of the plate and independent of each other and extending longitudinally of the plate, the two 90 socket members united at the front end and forming a cross nose with a central opening extending therethrough in a straight longitudinal line, and an endwise yieldable gripper jaw for each socket member carried by and 95 independently movable in its socket member, each gripper jaw having its acting end extending into the opening of the cross nose and having on its front side an acting face 100 diagonally of the body of the jaw and inwardly extending in a plane parallel with the center of the nose opening, for a rear draw on the plate to force the gripping faces of the jaws into engagement with the wire, substantially as described.

JUAN H. REECE.
